ROTARY IRONER

**George W. Dunham, Westport, Conn., assignor to
General Electric Company, a corporation of
New York**

Application February 18, 1937, Serial No. 126,373

22 Claims. (Cl. 38—61)

The present invention relates to ironing machines of the type in which ironing is effected between a heated shoe and a padded roll.

The object of my invention is to provide an improved construction and arrangement in ironing machines of this type, and for a consideration of what I believe to be novel and my invention, attention is directed to the accompanying description and the claims appended thereto.

10 In the accompanying drawings, Fig. 1 is a perspective view of an ironer embodying my invention; Fig. 2 is a front elevation of the ironer in section along line 2—2 of Fig. 3; Fig. 3 is an end elevation in section along line 3—3 of Fig. 2; Fig. 15 4 is a top plan view of the ironer housing partly broken away to show the driving mechanism; Fig. 5 is an end elevation in section along line 5—5 of Fig. 2, the shoe being shown pressed against the roll; Fig. 6 is a view similar to Fig. 5, the shoe 20 being moved away from the roll; Fig. 7 is a fragmentary view showing the arrangement for supporting the shoe; Fig. 8 is a sectional view taken on line 8—8 of Fig. 7; Fig. 9 is a perspective view 25 of the bracket connecting the shoe to the shoe supporting arm; Fig. 10 is a fragmentary sectional view showing the manner of securing the cover to the shoe; Fig. 11 is a rear elevation of the ironer; Fig. 12 is a view showing the shoe moved to a position in which its work contacting 30 face can be cleaned; Figs. 13 and 14 are perspective views of the pawl and detent connecting the shoe operating shaft to the mechanism for moving the shoe toward and away from the roll; Fig. 15 is an end elevation in section along line 15—15 35 of Fig. 2; Fig. 16 is a sectional view on line 16—16 of Fig. 15; Fig. 17 is a perspective view of the lever and the parts associated therewith controlling the driving connection to the roll; Fig. 18 is an enlarged perspective view of the driving 40 mechanism for the ironer; and Fig. 19 is an elevation of a mechanism for moving the shoe toward and away from the roll which may be substituted for the eccentric and eccentric strap illustrated in the other figures.

45 Referring to the drawing, the ironer comprises a shoe 1 and a roll 2 which are carried by a housing 3 containing mechanism for rotating the roll and for moving the shoe toward and away from the roll. The housing is secured to 50 the top 4 of a suitable table by bolts 4a threaded into lugs 4b on the housing (see Fig. 2).

The shoe comprises an arcuate metal plate 5 which is heated by suitable electric heating elements (not shown). On the upper surface of the plate are secured studs 6 to which is fastened

a shoe cover 7. At the center of the plate 5 is secured a bracket 8 having arms 9 which are pivotally connected to an arm 10 by means of a pin 11. The arm 10, which serves as the shoe supporting arm, is keyed to a shaft 12. When the shaft 12 is oscillated, the shoe is moved toward and away from the roll. The shaft 12 is journaled in a tube 13 which is fixed in a boss 14 (Fig. 4) in the side walls of the ironer housing.

The roll comprises a sheet metal cylinder 15 having disks 16 and 17 at each end secured thereto respectively by means of flanges 18 and 19 secured to the inner surface of the cylinder. On the outer surface of the cylinder 15 is a pad 20 which is held thereon by means of a pad cover 21. The pad cover is held in place by means of snap rings 22 which fit in grooves 23 in the flanges 18 and 19. The disk 17 is secured to the flange 24 of a sleeve 25 carrying a sleeve bearing 26 which rotatably supports the roll on a tube 27 fixed in a boss 28 in the ironer housing. The disk 16 is fixed to a sleeve 29 which is keyed to a shaft 30 journaled in the tube 27. The roll is rotated by the shaft 30 through the driving connection formed by the sleeve 29 and the disk 16. 25

The ironer is operated by an electric motor 31 which is resiliently supported from a plate 32 by means of arms 33 having openings 34 which are snapped into grooves in rubber bushings 35. The plate 32 is secured to the underside of the table top by the bolts 4a. The compression of the rubber bushings, and therefore the resilience of the mounting, is varied by means of nuts 36 which are threaded on spindles 37 secured to the plate 32. The motor shaft 38 is slotted to receive a bar 39 which fits in the slotted end of a shaft 40 and serves as a coupling between the shafts. The shaft 40 is journaled in a boss 41 which is integral with a web 42 extending across the side walls of the ironer housing. The shaft 40 has cut therein a worm 43 which meshes with a worm wheel 44 rotatably carried on the roll driving shaft 30. The thrust of the worm shaft 40 is taken by a ball 45 which bears against the end of plug 46 threaded in the top wall of the ironer housing. After adjustment, the plug 46 is prevented from turning by means of a set screw 47.

Integral with the worm gear 44 is a hub having a pinion 48 cut therein and having a bearing surface 49 on which is rotatably carried the hub 50 of internal gear 51. The internal gear 51 meshes with gears 52 which are rotatably carried on stub shafts 53 fixed to an arm 54 which is pinned to the roll driving shaft 30. The gears 52 also mesh with the pinion 48. The pinion 48, the internal

gear 51, the gears 52 and the arm 54 comprise an epicyclic or planetary gear train which provides a speed reducing driving connection between the continuously rotating worm wheel 44 and the roll driving shaft 30. When the rotation of the internal gear 51 is not restrained, the friction in the bearings of the roll shaft 30 is sufficient to hold the roll shaft stationary. When the internal gear 51 is held stationary, the planetary gearing provides a speed reducing driving connection to the roll shaft. For holding the internal gear stationary, I have provided a control lever 55 (see Figs. 2 and 17) which is pivoted on a pin 56 carried in bosses 57. The control lever 55 has an arm 58 having a hooked end 58a which is adapted to fit in depressions 59 in a flange 60 on the internal gear 51. The lever 55 is controlled in a manner which will hereinafter be described.

20 The shoe is moved toward and away from the roll by means of an eccentric 61 which is rotatably supported on the tube 27 adjacent the side wall of the ironer housing. It is important that the eccentric be supported adjacent the side wall 25 of the ironer housing since the forces exerted by the eccentric are large. If, for example, the eccentric were supported on the free or unsupported end of the shaft 30, i. e., on the part where the planetary gearing is located, the boss 28 and the tube 27 would have to be made much more rigid. On the eccentric is an eccentric strap 62 which has a ball-and-socket connection with crank arm 64. The arm 64 has spaced side walls 64a carrying a pin 64b therebetween on which is pivoted thereon a pawl 65. The pawl has a tongue 66 adapted to fit in a slot 67 in a collar 68 keyed to the shoe operating shaft 12. The pawl is biased into engagement with the slot 67 by means of a spring 69. When the tongue 66 engages the slot 67, the arm 64 is fixed to the shoe operating shaft 12. The arm 64 has a socket for a ball 70 which engages the upper end of a shaft 71 slidably carried in a boss 72 in the web 42. A suitable packing 73 is provided in the boss 72 to prevent the leakage of lubricant around the shaft. The shaft 71 is biased upwardly by means of a coil spring 74 arranged between a seat 75 on the shaft and a seat 76 on a rod 77 which is threaded into a nut 78 fixed in the plate 32. The compression of the spring 74 is adjusted by threading the rod into and out of the nut 78, a handle 79 being provided on the rod for the convenience of the operator. The force of the spring 74 tends to move the shoe toward the roll and the eccentric 45 is therefore used only for moving the shoe away from the roll. This manner of operating the shoe provides substantially uniform pressure between the shoe and the roll regardless of variations in the thickness of the ironer pad and of the material being ironed. When the shoe is pressed against the roll, the parts of the ball and socket joint 63 are separated, the separation depending on the thickness of the material between the roll and the shoe.

65 Integral with the eccentric 61 is a circular flange 80 (Figs. 2 and 15) having a radial slot in which is slidably carried a key 81. The key is urged outward by means of a spring 82, the outward movement of the key being limited by engagement of a tongue 83 on the key with a shoulder 84. When the parts are in the position shown in the drawings, the key is held in its inner position by engagement with one of the ends 85 of a C-shaped trip lever 86. The trip lever is loosely mounted on pins 87 fixed in bosses 88 and is

resiliently held against the faces of the bosses by means of coil springs 89 (see Fig. 16). The ends of the trip lever are moved out of the path of the key 81 by means of an arm 90 fixed to a shaft 91 journaled in a boss 91a in the web 42. When the shaft 91 is moved in a clockwise direction, as viewed in Fig. 16, the ends 85 of the trip lever 86 are moved toward the roll to a position out of contact with the key 81. The key 81 is then moved outward by the spring 82 into engagement with one of a plurality of notches 92 (Fig. 4) in a flange 93 integral with the continuously driven worm wheel 44, thereby completing a driving connection between the worm wheel and the eccentric. Once the driving connection is completed, the trip lever 86 is allowed to be returned to its normal position by the springs 89. The shaft 91 is returned to its normal position by a coil spring 91b which tends to turn the shaft in a counter-clockwise direction, as viewed in Fig. 16. The rotation of the eccentric continues through 180° until the key 81 comes in contact with the other end 85 of the trip lever. This end moves the key inward and breaks the driving connection to the eccentric.

In order to insure a greater separation between the key and the notch 92 a C-shaped spring 94 is loosely mounted on a pin 94a on the trip lever. The ends of the spring are normally closer together than the ends of the trip lever. The spring is not strong enough to move the key out of engagement with the notch 92, but it is strong enough to move the key inward after the key has been moved out of the notch 92 by the trip lever. The ends of the spring 94 normally ride on the flange 80 so that it is not necessary to provide a rigid support for the spring.

The trip lever 86 is so arranged that at the end of each 180° movement of the eccentric, the eccentric occupies either the position shown in Fig. 5 in which the shoe is pressed against the roll or the position shown in Fig. 6 in which the shoe is moved away from the roll. Any tendency to overtravel of the eccentric is prevented by the friction between the eccentric and the tube 27, which friction is further increased by a coil spring 95 carried in a circular opening in the eccentric and bearing on the tube 27. The spring 94 urges a ball 95a outward and when the eccentric is in the positions shown in Figs. 5 and 6, the ball fits in one of the notches 96 in the eccentric strap. The spring pressed ball 95a serves as a detent for molding the eccentric strap in proper relation to the eccentric.

When the ironer is used for continuous ironing, it is desirable that the rotation of the roll be started and stopped in accordance with the position of the shoe. That is, the roll should be stationary when the shoe is away from the roll and the roll should rotate when the shoe is pressed against the roll. This is effected by means of a cam 97 (see Fig. 17), integral with the eccentric 61, which engages an arm 98 on the control lever 55. The arm 98 is held against the cam 97 by means of a coil spring 99 arranged between a boss 100 (Fig. 3) in the ironer housing and a seat 101 in the upper side of the arm. The shape of the cam 97 is such that the hooked end 58a of the arm 58 is moved into engagement with one of the notches 59 when the shoe is pressed against the roll and is moved out of engagement with the notch when the shoe is moved away from the roll. The rotation of the roll, which is started upon engagement of the hooked end 58a with one of the notches 59, starts somewhat before the develop- 75

ment of the full pressure between the roll and the shoe. This reduces the starting load on the roll driving mechanism.

When the ironer is used for pressing it is desirable that the roll remain stationary when the shoe is pressed against the roll. This is effected by means of a hand lever 102 (see Fig. 4) fixed on a shaft 103 journaled in the front wall of the ironer housing. On the inner end of the shaft 103 is fixed a lever 104 (Fig. 17) which when moved to a vertical position lifts the arm 98 to a position where the hooked end 58a of arm 58 is clear of the notches 59. As long as the lever 104 is held in this position the roll remains stationary. The lever 102 is held stationary with reference to the ironer housing by means of a spring pressed ball detent 102a.

The ironer is controlled by means of a lever or knee pad 105 which is fixed to a shaft 106 by means of a set screw 107 (Fig. 15). The shaft 106 is slidably carried in brackets 108 on the underside of the table top. The righthand end of the shaft, as viewed in Fig. 4, bears against an arm 109 fixed on the shaft 91. Movement of the lever 105 to the right causes the shaft 91 to be turned in a clockwise direction, as viewed in Fig. 16, thereby moving the ends 85 of the trip lever 86 clear of the key 81 so that the spring 82 can move the key into one of the slots 92 to complete a driving connection to the eccentric. As soon as the driving connection is completed, which requires only a very short interval due to the large number of slots 92 and the relatively high speed of rotation of the worm wheel 44, the lever 105 is released and the shaft 91 is returned to its normal position by means of the springs 89 acting on the trip lever 86 and the coil spring 91b turning the shaft 91. When the eccentric is rotated through 180°, the key is moved out of the slot 92 by engagement with one of the ends 85 of the trip lever 86 as described above.

The movement of the shoe toward and away from the roll may also be controlled by means of the lever 102. When the lever 102 is moved to a vertical position projecting upward from the shaft 103, a movement of the upper end of the lever toward the left as viewed in Fig. 1 will cause the cam lever 104 to engage the center of the trip lever 86 and move it toward the right as viewed in Fig. 4. This causes the ends 85 of the trip lever to be moved to the left as viewed in Fig. 4 to a position in which they are clear of the key 81. The key 81 is then moved outwardly into one of the notches 92 under the action of the spring 82 to complete a driving connection from the worm gear 44 to the eccentric 61. As soon as this driving connection is completed the lever 102 may be released and it will be returned to the vertical position by means of the coil spring 89 which tends to return the trip lever 86 to the position shown in Fig. 4.

Similarly, when the lever 102 is turned to the pressing position, i. e., the position in which it projects downwardly from the shaft 103, it can likewise be used to control the driving connection to the eccentric. When in this position movement of the lower end of the lever 102 to the left as viewed in Fig. 1 causes the lever 104 to engage the trip lever 86 and move it to a position permitting the key 81 to move outward into one of the slots 92 and complete a driving connection from the worm gear 44 to the eccentric. Upon release of the lever 102, after completion of the driving connection, it will be returned to

the vertical position by means of the springs 89 acting on the trip lever 86.

The lever 105 is also used to effect the release of the pressure between the roll and the shoe in case of failure of the power supply. This is effected by means of a downward movement of the lever which causes the shaft 106 to rotate in a counterclockwise direction as viewed in Fig. 5. The shaft 106 has a lever 110 fixed thereto which bears against the lower end of a rod 111 10 slidably carried in the plate 32 and the web 42. The rod 111 is biased downward to the position shown in Fig. 5 by means of a coil spring 112. A washer 113 which engages the upper side of the table top serves as a stop which limits the 15 downward movement of the rod. When the shaft 106 is moved in a counterclockwise direction as viewed in Fig. 5, the rod 111 is moved upward, its upper end striking the pawl 65 and moving the tongue 66 out of the notch 67. The 20 shoe will then move away from the roll due to the energy stored by the flexing of the shoe and roll supporting parts. The rearward movement of the shoe will stop when a spring-pressed detent 114 carried in the web 42 engages a notch 25 115 in the collar 68. In this position the tongue 66 is adjacent a shoulder 116 on the collar 68. The eccentric, eccentric strap, and the arm 64 remain stationary during this movement.

Upon movement of the control lever 105 to the 30 right, as viewed in Fig. 1, the eccentric is turned 180° from the position shown in Fig. 5 to the position shown in Fig. 6. During this movement the detent 114 holds the collar 68 stationary and the eccentric moves the arm 64 to the 35 position shown in Fig. 6. When the arm 64 reaches this position the tongue 66 is moved into the slot 67 by the spring 69, thus re-establishing the connection between the shoe operating shaft and the eccentric.

The same mechanism which serves as an emergency release, also serves to permit the movement of the shoe to a position in which the work contacting face of the shoe can be cleaned. This is effected by moving the lever 105 downward when the parts are in the position shown in Fig. 6. This movement of the lever causes the rod 111 to engage the detent 65 and lift the tongue 66 out of the slot 67. The shoe may now be grasped and bodily moved rearward to the 50 position shown in Fig. 12. This movement of the shoe is slightly resisted by the detent 114. Upon the completion of the cleaning of the shoe, the driving connection between the shoe and the eccentric can be automatically reestablished by 55 operating the control lever 105 to cause the turning of the eccentric. At the start, the eccentric is in the position shown in Figs. 6 and 12. Upon turning of the eccentric through 180°, the tongue 66 co-operates with the shoulder 116 to move 60 the collar 68 to the position shown in Fig. 6, where it is held by the detent 114. The shoe operating shaft is now in the position shown in Fig. 6, and the eccentric, the eccentric strap, and the arm 64 are in the position shown in Fig. 5. 65 During the next 180° movement of the eccentric the collar 68 is held stationary by the detent 114 and the arm 64 is moved from the position shown in Fig. 5 to the position shown in Fig. 6, in which position the tongue 66 is moved into the notch 70 67 by the spring 69. It is, therefore, apparent that upon release of the connection between the eccentric and the shoe the connection is automatically re-established by successive operation 75 of the eccentric.

In the use of the ironer, the material to be ironed is first arranged on the roll, the roll being stationary and the shoe away from the roll. The knee pad 105 is then moved to the right as viewed in Fig. 1, thereby moving the shaft 106 against the arm 109 and turning the shaft 91 in a clockwise direction as viewed in Fig. 16. The arm 90 which is fixed to the shaft 91 engages the trip lever 86 and pivots it about the studs 87 until the ends thereof are clear of the key 81. The key is then moved outward by the spring 82 into one of the slots 92 in the worm wheel 44, completing a driving connection from the worm wheel to the eccentric. As soon as this driving connection is completed, the knee pad is released and is returned to its normal position by the springs 89 acting on the trip lever 86 and by the coil spring 91b acting on the shaft 91. The driving connection to the eccentric remains completed until the eccentric has turned through 180 degrees at which time the key 81 is moved out of the slot 92 by engagement with one of the ends 85 of the trip lever. After being moved out of the slot 92, the key is moved further inward by engagement with the C-shaped spring 94. This prevents any clicking of the key against the edges of the slots 92.

The 180 degree rotation of the eccentric moves the eccentric from the position shown in Fig. 6 in which the shoe is separated from the roll to the position shown in Fig. 5, in which the shoe is pressed against the roll. The pressure between the shoe and the roll is developed by the spring 74, which acts through the rod 71 and the bracket 64 to turn the shoe supporting shaft 12 in a counterclockwise direction as viewed in Fig. 5. When the shoe is pressed against the roll, the parts of the ball and socket joint 63 are separated, the amount of separation depending upon the thickness of the pad and the thickness of the material being ironed.

When the eccentric is in the position shown in Fig. 5, the cam surface 97 which is integral with the eccentric occupies the position shown in Fig. 17. In this position the control lever 55 is moved to the position illustrated in which the hooked end 58a of the arm 58 is moved into one of the depressions 59 in the flange 60 on the internal gear 51. This holds the internal gear 51 stationary so that a driving connection is completed to the roll driving shaft 30 from the worm wheel 44 through the planetary gearing which comprises the pinion 48, the internal gear 51 and the gears 52. The shape of the cam 97 is such that the driving connection to the roll is completed before full ironing pressure is built up between the roll and the shoe. When the roll is rotating, the ironer is adapted for ironing flat work which is fed under the shoe by the rotation of the roll.

Under some circumstances it is desirable that the roll remain stationary. This is effected by turning the lever 102 in a clockwise direction from the position shown in Fig. 1 to a position in which it projects vertically downward. This causes the lever 104 to be moved in a clockwise direction to a position extending upward from the shaft 103. In this position, the upper end of the lever 104 engages the arm 98 of the lever 55 and holds it in a position in which the hooked end 58a is clear of the depression 59. While in this position, the roll remains stationary due to the fact that the friction in the roll and the roll driving shaft bearings is greater than the friction in the bearing of the gear 51.

The shoe is moved away from the roll by again

moving the knee pad 105 to the right as viewed in Fig. 1. This causes the eccentric to be turned through another 180 degrees in the manner described above. During this movement the eccentric strap 62 acts through the ball and socket joint 63 to move the shoe from the position shown in Fig. 5 to the position shown in Fig. 6. During this movement, the spring 74 is compressed. When the eccentric is in this position the cam 97 has turned 180 degrees from the position shown in Fig. 17 and has lifted the hooked end 58a clear of the depression 59, thus breaking the driving connection to the roll. The roll therefore remains stationary when the shoe is moved away from the roll and material to be ironed can be conveniently arranged on the roll.

In Fig. 19 is shown an alternative arrangement for moving the shoe toward and away from the roll. In this construction, the eccentric 61 is replaced by a gear 117 which is driven in the same manner as the eccentric. The gear 117 is integral with the casting which includes the cam 97, the flange 80, and the slots carrying the driving key 81. As in the previous construction, it is rotatably mounted on the boss 27. The gear 117 meshes with a gear 118 which is rotatably carried on a stub shaft 119 fixed in the side walls of the ironer housing. Integral with the gear 118 is a cam 120 which co-operates with an arm 121 fixed to the shoe operating shaft 12. The arm 121 is held against the cam 120 by a spring 122 arranged between a cup 123 in the ironer housing and a seat 124 on the arm 121. When the parts are in the position illustrated, the shoe is pressed against the roll. When the gears 117 and 118 have been turned 180 degrees from the position illustrated, the shoe is moved away from the roll. The cam 120 is provided with flat surfaces 125 which engage the flat surface 126 on the arm 121 in these positions. The flat surface on the long radius of the cam shown in Fig. 19 acts as a detent, prevents over-travel, and also positions the cam when spring 122 is compressed and consequently exerting its greatest force. This is desirable, for in this construction the friction is greatly reduced, and if without the flat, the cam did not stop at exactly the right position, the spring load might cause cam 120 to coast forward or backward, depending on which side of the center it stopped.

What I claim as new and desire to secure by Letters Patent of the United States is:

1. In an ironer of the type having a roll, a shoe, power means for effecting engagement and separation of the roll and the shoe, and means independent of said first means for releasing the pressure between the roll and the shoe, a shaft mounted for sliding and rotating movement, a lever for selectively sliding and rotating the shaft, and connections between said shaft and both of said means whereby operation of one of said means is effected by sliding movement of the shaft and operation of the other of said means is effected by rotation of said shaft.

2. In an ironer of the type having a roll, a shoe, power means for effecting engagement and separation of the roll and the shoe, and means independent of said first means for releasing the pressure between the roll and the shoe, a control lever mounted for movement in two planes, and connections between said lever and both of said means whereby operation of one of said means is effected by movement of the lever in one plane and operation of the other of said means is effected by movement of the lever in the other plane.

3. In an ironer of the type having a roll, a shoe, power means for effecting engagement and separation of the roll and the shoe, and means independent of said first means for releasing the pressure between the roll and the shoe, a control lever for selectively effecting operation of each of said means.
4. In an ironer of the type having a roll, a shoe, power means for effecting engagement and separation of the roll and the shoe, and means independent of said first means for releasing the pressure between the roll and the shoe, a control lever mounted for movement in two directions, and connections between both of said means and said lever whereby operation of one of said means is effected by movement of the control lever in one direction and operation of the other of said means is effected by movement of the control lever in the other direction.
5. In an ironer, a tube, a roll rotatably supported on the tube, a shaft extending through the tube for rotating the roll, a shoe, means including eccentric means for moving the shoe toward and away from the roll, and reduction gearing for rotating the roll and operating said eccentric means, said gearing and eccentric means surrounding said shaft.
6. In an ironer, a frame having a tubular sleeve, a roll rotatably supported on the sleeve, a shaft extending through the sleeve for rotating the roll, a shoe, eccentric means mounted on the sleeve, means including said eccentric means for moving the shoe toward and away from the roll, and reduction gearing for rotating the shaft and the eccentric means, said reduction gearing being mounted on said shaft.
7. In an ironer, a roll, a shoe, a gear, means including eccentric means connectable to said gear for effecting relative movement of the roll and the shoe toward and away from each other, a shaft for rotating the roll extending through said gear and said eccentric means, and epicyclic gearing mounted on said shaft for effecting a driving connection from said gear to said shaft.
8. In an ironer, a casing, a tube extending from a wall of said casing, a roll rotatably supported on said tube, a shaft extending through the tube for rotating the roll, eccentric means surrounding said tube adjacent said wall, reduction gearing concentric with and surrounding said shaft for rotating said shaft and said eccentric means, a shoe, and means including said eccentric means for moving said shoe toward and away from the roll.
9. In an ironer, a casing, a tube carried by a wall of said casing and having an unsupported end within the casing, a roll rotatably supported on said tube, eccentric means rotatably supported on said tube adjacent said wall, a shoe, means for effecting movement of the shoe toward and away from the roll including means operated by rotation of said eccentric means, and means for rotating the eccentric means.
10. In an ironer, a casing, a tube carried by a wall of the casing, a roll rotatably supported on the tube, a shaft extending through the tube for rotating the roll, said shaft having an unsupported end within said casing, reduction gearing on said unsupported end for rotating said shaft, eccentric means within said casing between said gearing and said wall, said eccentric means surrounding said shaft, a shoe, and means including connections between said shoe and said eccentric means to move the shoe toward and away from the roll.
11. In an ironer, a casing, a tube carried by a wall of the casing, a roll rotatably supported on the tube, a shaft extending through the tube for rotating the roll, said shaft having a free end within said casing, gearing for rotating the shaft comprising a common drive gear and epicyclic gearing driven thereby and having a connection with the shaft, a shoe, eccentric means, means for effecting movement of the shoe toward and away from the roll including means operated by rotation of said eccentric means, and clutch means between said common drive gear and the eccentric means for selectively rotating the eccentric means, said eccentric means being arranged between said gearing and said wall, and said eccentric means and said gearing all surrounding said shaft.
12. In an ironer, a casing, a roll, a shoe, a roll driving shaft journaled in the casing having a driving connection to the roll and having a free end within the casing, eccentric means, means for effecting movement of the shoe toward and away from the roll including means operated by rotation of said eccentric means, reduction gearing for rotating the roll, and clutch means between said gearing and the eccentric means for selectively rotating the eccentric means, said eccentric means and said gearing surrounding the free end of said shaft.
13. In an ironer, a roll, a shoe, a shaft for rotating the roll, a common drive gear loose on said shaft, epicyclic gearing carried on said shaft, said epicyclic gearing having a part driven by said gear, a part connected to said shaft, and an intermediate part, means including eccentric means connectable to said gear for effecting relative movement of the roll and the shoe toward and away from each other, and means controlled by said eccentric means for holding said intermediate part of the epicyclic gear stationary whereby a driving connection is effected to the shaft.
14. In an ironer, a roll, a shoe, a casing, a shaft carried by a wall of said casing and having a driving connection to the roll, said shaft having an unsupported end within the casing, reduction gearing on said unsupported end for rotating said shaft, eccentric means between said gearing and said wall, said eccentric means rotatably surrounding said shaft, and means for effecting relative movement of the roll and the shoe toward and away from each other including means operated by rotation of said eccentric means.
15. In an ironer, a roll, a shoe, a frame, a shaft journaled in said frame and having an unsupported end projecting therefrom, a common drive gear rotatable about and surrounding said shaft, epicyclic gearing on the unsupported end of said shaft for effecting a speed reducing connection between said common drive gear and said shaft, eccentric means between said epicyclic gearing and said frame, said eccentric means rotatably surrounding said shaft, means for effecting relative movement of the roll and the shoe toward and away from each other including means operated by rotation of said eccentric means, and clutch means between said common drive gear and said eccentric means.
16. In an ironer, a roll, a shoe, a shaft for rotating the roll, epicyclic gearing for rotating the shaft, and means including a rotatable member having connections with the shoe for effecting movement of the shoe toward and away from the roll, said rotatable member and said gearing

being spaced apart along and surrounding said shaft.

17. In an ironer, a roll, a shoe, a shaft for rotating the roll, a common drive gear, epicyclic gearing for rotating the shaft, a rotatable member connectable to said gear, and means operable by rotation of said member for effecting movement of the shoe toward and away from the roll, said common drive gear, epicyclic gearing and member being spaced apart along and surrounding said shaft.

18. In an ironer of the type having a roll, a shoe, and means for rotating the roll and for effecting relative movement of the roll and shoe toward and away from each other, a personally operable control means for controlling the relative movement of the roll and shoe, control means for stopping and starting the rotation of the roll in accordance with the relative position of the roll and shoe, a manually operable lever movable to stable positions rendering said roll control means respectively effective and ineffective, and means operable by said lever while in said stable positions for operating said first control means to cause relative movement of the roll and shoe.

19. In an ironer of the type having a roll, a shoe, means for rotating the roll, and means including a personally operable control for effecting relative movement of the roll and shoe toward and away from each other.

20. In an ironer, a roll, a shoe, means including an oscillatable shaft for moving the shoe toward and away from the roll upon oscillation of the shaft, power means for rotating the roll, a crank, mechanism connectable to said power means for oscillating said crank, means for establishing a connection between the crank and the shaft for oscillating the shaft to move the shoe toward and away from the roll upon oscillation of the crank, said connecting means being breakable to permit

movement of the shaft in one direction relative to the crank, and including a pawl and ratchet connection between said crank and said shaft for returning said shaft to the position establishing said first connection upon oscillation of said crank.

21. In an ironer, a driven shaft, a driving gear, an eccentric, and epicyclic gearing driven by said gear and connected to said shaft, all surrounding and spaced apart along said shaft, said epicyclic gearing having a rotatable part which when held stationary establishes a driving connection to the shaft through the gearing and when released permits the shaft to remain stationary while the gearing is driven, a breakable connection between said gear and eccentric for rotating the eccentric, and a lever having a part responsive to the position of the eccentric for releasing or holding stationary said rotatable part of the gearing in accordance with the position of the eccentric. 20

22. In an ironer, cooperating ironing members including a roll, means including a rotatable member for effecting relative movement of the ironing members toward and away from each other, a roll driving shaft, a driving gear, epicyclic gearing for rotating said shaft, said rotatable member, said gear, and said epicyclic gearing all spaced apart along and surrounding said shaft, said epicyclic gearing having a rotatable part which when held stationary establishes a driving connection to the shaft through the gearing and which when released permits the shaft to remain stationary while the gearing is driven, a breakable connection between said gear and said rotatable member, and a lever having a part responsive to the position of said rotatable member for releasing or holding stationary said rotatable part of the epicyclic gearing in accordance with the position of said rotatable member. 25 35
